UNITED STATES PATENT OFFICE.

JOHN EDWARD ERCANBRACK, OF CHICAGO, ILLINOIS.

WATER HEATER.

Application filed November 10, 1922. Serial No. 600,160.

To all whom it may concern:

Be it known that I, JOHN EDWARD ERCANBRACK, a citizen of the United States, residing at Chicago, in the county of Cook and State of Illinois, have invented a new and useful Improvement in a Water Heater, of which the following is a specification.

My present invention relates to water heaters, and more particularly to the type known as "auxiliary submerged heaters" that are submerged in the hot water either within the boiler or in a chamber outside the boiler through which the water of the boiler is circulated.

Among the divers objects of my invention are the provision of a heater of this character that is easy to install and which may be readily controlled. Also, it is an object of my invention to provide a structure of this kind that may be regulated, especially when two or more units are installed in the same heating apparatus. It is also an object of my invention to provide means for the ready assembly of the parts of the unit so that they may be easily adjusted and for the purpose of being able to remove the parts when it is desired to repair or clean the same. I also provide suitable means for checking a reverse circulation, and simple devices for supporting the inlet tube and coupling the same to the housing or head. Many other objects will be apparent to persons skilled in this art, and I prefer to carry out the divers objects in substantially the following manner. Reference will now be made to the accompanying drawings, in which—

Fig. 1 is a schematic view showing the front of a boiler and a storage tank with two of my heating units installed therein, one being a single unit and the other a twin unit.

Fig. 2 is a vertical central section on line 2—2, Fig. 1, looking in the direction of the arrows and drawn to an enlarged scale.

Fig. 3 is a vertical section on irregular line 3—3, Fig. 2, the view being taken through the two units.

Fig. 4 is a transverse section on line 4—4, Fig. 2, showing, on enlarged scale, one method of supporting the inner tube.

Fig. 5 is a view similar to Fig. 2 showing a modified construction of the unit casing,

the connecting of the inner tube and the method of supporting the latter. 55

Fig. 6 is a vertical sectional view on line 6—6, Fig. 5.

Fig. 7 is a horizontal fragmental section on line 7—7, Fig. 6, showing a modified coupling or elbow. 60

Fig. 8 is a transverse section on line 8—8, Fig. 5, showing a modified method of supporting the inner tube.

Fig. 9 is a vertical section on line 9—9, Fig. 6, illustrating the detail of the return pipe baffle. 65

Fig. 10 is a side elevation of the coupling or elbow shown in Figs. 5, 6 and 7.

Fig. 11 is a vertical longitudinal section, similar to Figs. 2 and 5, and illustrating a further modification of the structure wherein the control valve is positioned in axial alignment with the inner tube and the separate coupling is replaced by a flange. 70

Fig. 12 is a similar view of another modification illustrating another form of mounting the structure in the boiler or chamber containing the water from which heat is radiated. 75

Fig. 13 is a vertical section on line 13—13, Fig. 12.

Fig. 14 is a vertical section, similar to Fig. 13, showing a modified coupling in which two of the inner tubes are united by a Siamese coupling or elbow. 85

Fig. 15 is a vertical longitudinal section of a further modified construction, wherein the central tube is formed of two bent metal sheets and the inner valve is of the butterfly type. 90

Fig. 16 is a vertical section on line 16—16, Fig. 15, illustrating certain details thereof.

Fig. 17 is a vertical transverse section on an enlarged scale, taken on line 17—17, Fig. 15. 95

Figs. 18 and 19 are, respectively, an outer end view and a side elevation of the modified coupling or elbow employed in the modification illustrated in Figs. 15 and 16.

Fig. 20 is a side elevation or plan of the butterfly valve shown in Figs. 15 and 16. 100

So far as possible similar reference characters have been employed to designate like parts wherever they occur throughout the several views, and by referring to Fig. 1 it will be seen the structure is a typical in-

stallation of the preferred type of heater shown in detail in Figs. 3 and 4, and installed upon the front of a boiler furnace so that the heating tubes may be submerged in the water within the boiler, and the heated water may be held in a storage tank adjacent thereto. It will be understood, however, that the heating tubes may be inserted through the wall of a suitable casing or container and submerged in water circulating from the boiler or heater. In either event the structure is substantially the same.

In Fig. 1, A indicates the front of a boiler furnace and B the storage tank in which the hot water is stored by means of circulating pipes C, c and c'. The cold water in the lower portion of the storage tank circulates to the heaters through the return pipe F. After being heated it passes through feed branches c and c' and main feed C to the upper portion of the tank. The cold water supply to the hot water storage tank enters through feed pipe E' to the bottom portion through an extension of pipe E' or by direct connection at the bottom, and the heated water being in the upper part of the tank passes out to the hot water outlets or faucets through discharge pipe E. To secure an even delivery of hot water at the outlet fixtures in the building the water is circulated through the hot water service mains and branches by means for the supply return pipe D and its branches.

The structure for heating the water, which is submerged in the hot water of the heating boiler comprises a casing 1 that passes through the wall of the hot water container, either the boiler or a chamber connected therewith, and is maintained in position by means of an annulus 2 that is secured to wall α of the boiler or chamber by means of bolts 3, and the opening is made water proof by means of a gasket 4 at the inner portion of annulus 2, and, as seen in Fig. 2 of the drawings, the bore in the annulus is tapered inwardly, as at 5, to permit of a slight swivelling of casing 1. The inner end of casing 1 is closed by a plug 6 screwed, welded, or otherwise secured therein, and having a lateral stub 7 that projects through an aperture in a supporting wall γ to be maintained therein by means of a cotter pin, or the like. Mounted within casing 1 is an inner tube 8 which may be sectional, as shown in Fig. 2, or a continuous piece of tubing, as shown in the remaining figures of the drawings. This tube is not as long as casing 1 so that it terminates short of the inner end thereof and is open so as to discharge water into the casing. The tube 8 is supported by means of a suitable spider 9 at the end thereof and, when made in sections, a wider spider 9* may be employed so as to receive ends of an adjacent section and connect them together. The spider 9 or 9* occupies some

of the space between the tube and the inner wall of the casing so as to restrict the capacity thereof, and in order to avoid retardation of the circulation I provide discharge apertures 10 adjacent these spiders through which the return water may discharge before reaching the end of the tube.

The head or device to which the outer ends of the casing and the tube are connected preferably comprises a hollow casing or housing 11 having a stub in its upper portion that is bored and threaded to receive the vertically disposed discharge pipe c.

An irregular shaped part 13 in the upper portion of the housing divides the same into two chambers 14 and 15, into one (14) of which the return water from the tank and system is discharged, and from it passes into a coupling and into tube 8 where it becomes

partly heated and circulates back into the casing between the tube and the hot casing wall when it is entirely heated, and then into chamber 15 from which the heated water is distributed through pipe c.

The lower portion or wall 13 is provided with an outlet opening 16 that is countersunk to provide a valve seat upon its upper side and its lower portion is provided with a spherical bearing to receive the adjacent portion of the coupling element. This coupling wall

preferably consists of an elbow 17 of segmental shape comprising a quadrant in outline, the inlet end portion of which is ground spherical to fit the spherical seat upon the under portion of the opening in wall 13.

The outlet portion of this elbow is threaded to receive the adjacent threaded end of tube 8. A lug 18 is formed horizontally upon the elbow and is provided with a threaded aperture into which a bolt 19 is screwed so that its extended end will abut the bottom of chamber 16 and when said bolt has been sufficiently rotated it will elevate the elbow until its spherical end portion has been

fitted into the spherical seat above mentioned. A clean out opening is formed in housing 11 into chamber 15, preferably in alignment with the axis of tube 8 and is closed by a suitable plug 20 which may be removed to permit access to be had to adjust bolt 19, or for the purpose of removing the elbow and tube.

It frequently becomes necessary or desirable, when two or more units are installed in a boiler or hot water tank, to shut off one of the supply or return pipes, and in order to do this I have provided a threaded aperture in the upper portion of housing 11 into chamber 14. A mushroom valve 21, alining with the countersunk seat in aperture 16, is carried by a sleeve 22 that is exteriorly and internally threaded so that the exterior threads will be engaged with the threads in the aperture and the interior threads will be engaged with the threaded spindle or stem 130

120

125

130

23 of valve 21. The upper ends of the sleeve and the valve stem are, respectively, provided with transverse slots to receive a screw driver, or similar tool, for the purpose of 5 making adjustment, and, as seen in Fig. 2, the threaded aperture in which parts are mounted is closed by means of a threaded plug 24 that may be removed for the purpose of making adjustment and which when 10 screwed in position will avoid leakage. When it is desired to cut off one of the return pipes, plug 24 is removed and the valve adjusted.

When an installation of the type illustrated in Fig. 3 or any number of units is 15 made, the hot water is circulated from the top of the tank B to near the outlets or faucets through pipes E and D with their extensions and connecting branches. When a 20 considerable number of outlets or faucets are opened at any one time the hot water pipe D from the top of the tank will not ordinarily supply the full amount of water to supply the faucets and the down 25 flow in supply return pipe D is reversed; thus drawing cold water from the bottom of the tank through pipe F and chamber 14 of the housing to points in circulating supply system where it mixes with the hot water 30 drawn through pipe E at some of the supply outlets. This reverse flow of water is cold and naturally reduces the temperature of the warmer water delivered from distributing pipe E which is objectionable. In 35 order to avoid this, I have interposed a float ball valve between the unit housing and the system return pipe D. This is shown in detail in Fig. 3, and comprises a union 25 interiorly threaded at one end to receive return 40 pipe D, and exteriorly threaded at its opposite end to screw into a suitable threaded opening into a unit casing or housing. A seat 26 is made in the bore of the union, and fitted into the end of the union next housing 45 11 is a cage 27 that comprises a sleeve with guide ribs, the ends of which ribs are provided with soft metal projections 28 that are adapted to be turned inwardly after float ball 29 has been positioned therein. I prefer to employ a float ball so that it will rise 50 and ride upon the upper surface or ribs of the cage when moving from its seat 26 toward the extensions or projections 28.

The structure at the right side of Fig. 3 is 55 a detail of the twin housing employed in association with the unit structure at the left of said figure, all of the details being similar to those heretofore described in connection with the unit illustrated in longitudinal section at the left of said figure so that it need 60 not be specifically described herein, it of course being understood that the float ball valve is omitted in all units, excepting the one receiving the supply from return pipe D.

65 In Fig. 5 of the drawings, I have shown a

slightly modified construction wherein the dividing wall 30 of the housing 31 is in the lower portion thereof, and the return water flows into the lower chamber 32 and the heated water flows out of the upper chamber 33. The valve structure is the same as in the preceding sections, and the coupling element is enclosed upon its seat by means of bolt 19 abutting against the upper wall of the housing instead of the lower wall, as shown in Fig. 2. The coupling element, however, is slightly different in that the same comprises a tubular portion 34 having a vertical axis and the upper portion is open, as seen in Fig. 10 of the drawings, to provide a saddle 34^a so that tube 8 may be positioned therein and be brazed or welded in the concaved seat. The adjacent end of the tube abutting the vertical portion 34 of the coupling and said tube is provided with a cutout portion 36 that alines with the vertical tubular portion of the coupling. The coupling is mounted in a reverse manner to that shown in Fig. 2, and the end of tube 8 is provided with right angled slots so that the metal between the slots may be bent outwardly to provide feet 9^a, 9^b, to support the inner end of the tube. In lieu of the float ball valve illustrated in Fig. 3 of the drawings, when suitable check valves are installed in circulating branches between the hot water supply pipe E and supply return pipe D to prevent reverse flow in pipe D, and in order to prevent retarded circulation caused by two opposing currents meeting, I have provided a baffle 100 device positioned in union 25 between return pipe D and housing 31 which baffle comprises a holder in the form of a sleeve 35^a having laterally bent ends that project into chamber 32, and a pair of oppositely disposed disks 36^a are mounted upon opposite sides of the laterally bent ends by means of a clamping screw 37 so that the water flowing through pipe D and union 25 will pass 105 around the periphery of baffle disks 36^a.

In Fig. 12 of the drawings the unit in the form of housing 11 and all of the parts contained therein are exactly similar to the structure illustrated in Figs. 2 and 3 of the drawings. The tube 8 has its inner end provided with recesses 38 and the metal between the recesses is curved or curled outwardly to provide feet 39 that engage the inner surface of the casing. In this instance the casing is a drawn metal tube 40 having its inner end 115 hemi-spherical and having its outer end provided with an annular lip 41. A flange collar 42 is screwed into the opening wall and the body of this collar 42 is sufficient to receive the outer end portion of casing 40 with flange 41 overlying the outer surface of the flange of the collar. An element 43 of tubular shape is threaded at its outer end into housing 11 and has an annular flange 44 fitted substantially against the flange of cas- 125 130

ing 40 and concentric with the flange on collar 42. Bolts 45 connect these two flanges so that flange 41 of the casing is firmly held therebetween.

5 In Fig. 11 the wall of the hot water container is shown as provided with an enlarged opening α^1 through which casing 1 is inserted into the hot water therein, and in order to prevent leakage the face plate 46 10 has a gasket 47 interposed between it and the wall, and said plate is clamped in position by bolts 48. The face plate is provided with an embossment 49 that is bored and surrounds casing 1, and a gland nut 50 is 15 screwed into the stuffing box provided by the said embossment to compress the packing or other material 51 positioned therein, all of which structure prevents the leakage of the water contained within wall α . In this 20 modification the inner end of inner tube 8 is supported by means of lateral studs or rivets 52 that are of conical shape so as to rest against the inner surface of the casing 1. The outer surface of casing 1 has the 25 housing 53 mounted thereon and which is of cylindrical shape and disposed concentric with the axis of casing 1 and inner tube 8. A partition wall 54 divides the interior of the housing into a forward chamber 55 and a 30 rear chamber 56, the latter of which is in communication with the outlet or distributing pipe c . The inner tube 8 is screwed into an internally threaded flange 57 that has its edge cone shaped to fit a correspondingly 35 shaped aperture in the partition wall in which it is secured by a bolt or screw 57^a, the head of which overlies the surface of both flange 57 and partition 54. The outer portion of the opening in flange 57 is counter- 40 sunk, as at 58, to provide a seat for valve 21 which is of the construction heretofore described in connection with the preceding figures, and which is disposed in axial alignment with the inner tube 8. The dimension 45 of the aperture in partition 54 is equal to the internal dimension of casing 1 to permit access thereto. For convenience in mounting, the valve is positioned in a plug 59 in the outer end of housing 53 so that the entire 50 valve structure may be removed by removing plug 59 and the inner tube and flange may also be taken out therethrough. The inlet port 60 for the return water from the system, which is received through pipe D is 55 lateral to the valve and inner tube 8.

In Figs. 13 and 14, I have illustrated a slightly modified twin or Siamese housing, in all respects similar to that shown at the right hand of Fig. 3, with the exception that 60 instead of having the inner tubes receiving the water from which the upper chamber 15 through separate couplings or elbows, I have provided a Y or three way coupling 61 having two parallel branches 62 that are connected 65 suitable to the outer ends of parallel inner

tubes 8 and with a single inlet stub 63, having the heretofore described spherical seating portion that is positioned in a suitable recess surrounding a communicating aperture 16 between the upper and lower chambers 70 of the housing. This dispenses with the necessity of using two control valves 21, and, as seen, a single valve is all that is required.

In Figs. 15 to 20, I have illustrated a structure wherein the inner member of the 75 heater in the form of a tube or circular cross-section is dispensed with, and in lieu thereof I have positioned in casing 1 a pair of opposed sheets of metal 64 formed angular in a longitudinal line and positioned 80 within the casing so as to provide a conduit of diamond shape in cross-section. The height of the structure is exactly sufficient to be positioned, as shown in Figs. 15 and 17, with the major axis vertical. The outer end 85 of casing 1 is screwed into a housing 65 having upper and lower chambers as in the other forms of my invention, to the upper chamber of which is connected the distributing or outlet pipe c with the lower chamber 90 of which is connected return pipe F and supply return D. An irregular shaped hollow plug 66 is positioned in an opening aligning with casing 1, and has an inverted V-shaped arch 67 extending from its inner face 95 to receive the adjacent ends of strips 64, which are brazed or welded therein against the inner surface of the arch. This permits the lower portions of strips 64 within said arch to be cut away, as at 68, so that the cut away portion will register with a passageway 69 in communication with the lower chamber of the housing, which passageway is controlled by a butterfly valve 70, in the manner shown in Figs. 15 and 16. In 100 this construction housing 65 is provided with an attachment flange 71, through which bolts 72 are passed into the wall for the purpose of securing the structure in position. The return or feed water passes from the 105 lower chamber of housing 65 through the passageway 69 and the cut out portion 68 of the diamond shaped inner element and flows to the rear thereof, where it passes around the end of said element to the chamber between the same and the casing 1 and then flows outwardly into the upper chamber of housing 65 and is distributed in the system through discharge pipe c . The butterfly valve 70 need not be of the circular type, as 110 shown in Fig. 15, but may be elliptical in shape, as shown at 73 in Fig. 20. The stem 74 of the valve is oblique to the axis of casing 1, and is provided with any suitable stuffing box arrangement 75 at its outer end to prevent leakage.

In order to relieve the housing of air that might otherwise accumulate therein and check the flow of water through the system, I have provided a vent passage 80 be- 115 120 125

tween chambers 14 and 15 in the housing;— in Figs. 2, 11 and 12 the vent is shown through the dividing or partition wall, and in Figs. 5, 15 and 16 the same is through 5 the inner tube or coupling, or both.

What I claim is:—

1. A water heater comprising inner and outer conduit members adapted to be submerged in a body of hot water, a housing 10 within which the outer ends of said conduit members terminate, an apertured partition within said housing dividing the same into two chambers into one of which the outer conduit member discharges, an elbow 15 within said last mentioned chamber and connected to the adjacent end of said inner conduit member, the opposite end of said elbow engaging said partition at the aperture therein, and a threaded device carried 20 by said elbow and engaged with said housing whereby said elbow is maintained in engagement with said partition.

2. A water heater comprising inner and outer conduit members adapted to be submerged in a body of hot water, a housing 25 within which the outer ends of said conduit members terminate, an apertured partition within said housing dividing the same into two chambers into one of which the outer 30 conduit member discharges, an elbow within said last mentioned chamber and connected to the adjacent end of said inner conduit member, the opposite end of said elbow engaging said partition at the aperture therein, 35 a threaded device carried by said elbow and engaged with said housing whereby said elbow is maintained in engagement with said partition, and a valve within the chamber opposite said elbow for controlling the flow 40 through the elbow.

3. In a water heater, a suitable housing, an apertured partition dividing the same into two chambers, inner and outer conduit members terminating at one end within said 45 housing and communicating, respectively, with said chambers, an elbow coupling connecting the inner conduit member with its respective chamber through the aperture in said partition; said housing provided with a

threaded aperture opposite the aperture in 50 said partition, a sleeve threaded interiorly and exteriorly and screwed into said housing aperture, and a valve adapted to be seated in the partition aperture and having a threaded stem screwed into said sleeve 55 whereby to adjust said valve.

4. A water heater comprising inner and outer conduit members adapted to be submerged in a body of hot water, a housing 60 within which the outer ends of said conduit members terminate, an apertured partition integrally formed with said housing dividing the same into two chambers, into one of which the conduit member discharges, a connection element within said last-mentioned 65 chamber and connected to the adjacent end of said inner conduit member, the opposite end of said element engaging said partition at the aperture therein, and threaded means 70 engaged with the housing structure and said connection element whereby the latter is maintained in engagement with said partition.

5. A water heater comprising inner and outer conduit members adapted to be submerged in a body of hot water, a housing 75 within which the outer ends of said conduit members terminate, an apertured partition integrally formed with said housing dividing the same into two chambers into one 80 of which the outer conduit member discharges, a connection element within said last-mentioned chamber and connected to the adjacent end of said inner conduit member, the opposite end of said element 85 engaging said partition at the aperture therein, threaded means engaged with the housing structure and said connection element whereby the latter is maintained in engagement 90 with said partition, and a valve within the chamber opposite said connection element for controlling the flow through the latter.

Signed at Chicago, county of Cook and State of Illinois this 3d day of November, 1922.

JOHN EDWARD ERCANBRACK.

Witness:

FLORENCE MITCHELL.
